UNITED STATES PATENT OFFICE.

ROBERT PEARSALL SMITH, OF PHILADELPHIA, PENNSYLVANIA, ASSIGNOR
TO HIMSELF, JAMES WHITALL, CHARLES ROBERTS, AND W. H. NICHOL-
SON, OF SAME PLACE, J. M. MICKLE, OF MILLVILLE, NEW JERSEY, AND
CHARLES A. TATUM, OF NEW YORK, N. Y.

GLASS BOTTLE AND GLASS STOPPER.

SPECIFICATION forming part of Letters Patent No. 225,654, dated March 16, 1880.

Application filed February 6, 1880.

To all whom it may concern:

Be it known that I, ROBERT PEARSALL SMITH, a citizen of the United States, residing in Philadelphia, Pennsylvania, have invented 5 an Improvement in Glass Bottles and Glass Covers for the same, of which the following is a specification.

The objects of my invention are, first, to make a glass bottle-cover in the peculiar manner described hereinafter, for the permanent retention therein of a cork ring or lining; and, second, to so combine the said cover and its cork ring with the neck of a bottle, and with a shoulder thereon, that while the cover will 15 fit sufficiently tight to the upper edge of the neck of the bottle it can be readily detached from the same.

In the accompanying drawings, Figure 1 is a view, partly in section, of my improved bottle and of the cover, wholly in section; and Fig. 2, the same as Fig. 1, with the cover applied to the mouth of the bottle.

The bottles to which my invention is most applicable are such as are used by druggists 25 and others for putting up pomades, cosmetics, &c., in small quantities for purchasers.

A is the body of the bottle; a, the neck, which is so constructed as to form an external shoulder, b.

30 The flange e of the glass cover B is, preferably, made on a slight taper, so as to be larger in diameter below than above, and this flange terminates at its lower edge in an internally-projecting annular rib, f.

35 At the junction of the flange e with the top m of the cover there is an internal recess, n, bounded laterally in one direction by the flange e, and in the other by an annular rib, p, projecting downward from the top m of the cover.

40 Within the cover, and bearing against the interior of the flange e, is a ring, D, of cork, or a strip of cork bent to the form of a ring, the lower edge of which bears on the internal rib, f, the upper edge fitting into the annular recess n. After this cork ring has been forced

tight into its place it cannot be easily removed, as it is confined vertically by the rib f, and laterally in the annular recess n.

It should be understood that the cover, 50 while intended to fit tight enough, through the medium of the cork ring, to exclude air from the interior of the bottle, should admit of being detached with a very slight effort, the cork fitting tight enough to the neck to 55 permit the cover to have a slight frictional hold of the same, so that it cannot be shaken loose; but the cork should not prevent the ready application of the cover to the neck of the bottle.

In order to meet these requirements, the cork ring D is tapering—that is, the ring is larger in internal diameter below than above—while the neck of the bottle may be cylindrical, or nearly so; hence in applying the cover 65 it will fit freely over the neck in the first instance; but on depressing the cover the cork will embrace the upper edge of the neck. To permit the cover to be depressed to an unlimited extent, however, would result, in many 70 cases, in too tight a fit; hence the external shoulder, b, on the bottle, on which the lower edge of the glass cover bears when properly fitted to the neck, and which limits the penetration of the neck into the cover.

75 The upper edge of the neck, when the cover is depressed to its place, will indent the interior of the cork at x, where a permanent bearing for the edge of the neck is made, and this bearing insures a proper tight joint and a 80 sufficient frictional hold of the cover on the neck without preventing the ready removal of the cover with a very slight effort.

I am aware that covers have been made with elastic linings to fit to the exterior of the 85 necks of vessels. This, therefore, I do not claim, broadly; but

I claim as my invention—

1. The glass cover B, having an internal annular recess, n, at the junction of the flange 90 e with the top m, and an internal rib, f, projecting from the lower edge of the said flange,

all being constructed for the reception and retention of the cork ring, and for application to the neck of a bottle, as set forth.

2. The combination of the glass cover B 5 and its tapering cork ring D, fitted within the cover, as set forth, with a bottle having an external shoulder, b, for limiting the penetration of the neck into the cover, as described.

In testimony whereof I have signed my name to this specification in the presence of 10 two subscribing witnesses.

ROBERT PEARSALL SMITH.
